DESIGN FOR A BELL CANDLE OR THE LIKE

George Lamont, Los Angeles, Calif.

Application April 20, 1935, Serial No. 56,480

Term of patent 7 years

To all whom it may concern:

Be it known that I, George Lamont, a citizen of the United States, residing at Los Angeles, in the county of Los Angeles and State of California, have invented a new, original, and ornamental Design for a Bell Candle or the like, of which the following is a specification, reference being had to the accompanying drawing, forming a part thereof.

Fig. 1 is the front view of the bell candle showing my new design.

Fig. 2 is a side view of the bell candle shown in Fig. 1.

The dominant feature of the design resides in the surface ornamentation.

I claim:

The ornamental design for a bell candle or the like as shown and described.

GEORGE LAMONT.
